CIGARETTE DISPENSER

David Sachs, Bronx, N. Y.

Application October 18, 1952, Serial No. 315,543

1 Claim. (Cl. 221—196)

1

This invention relates to cigarette dispensers. It is an object of the present invention to provide a cigarette dispenser which will deliver a cigarette upon the turning of a manually operable dial and which at the same time serves as an attractive humidor for the cigarettes remaining therewithin.

It is another object of the present invention to provide a cigarette dispenser in which the cigarettes are gravity fed in a novel manner to a delivery chute upon the turning of a conveyor roller.

It is still another object of the present invention to provide a cigarette dispenser of the above type which may be conveniently used as a paper weight, and which is provided with a transparent door which reveals at all times the supply of cigarettes remaining within the dispenser.

It is still another object of the present invention to provide a cigarette dispenser of the above type which includes novel means for feeding the cigarettes one at a time.

Other objects of the invention are to provide a cigarette dispenser bearing the above objects in mind which is of simple construction, inexpensive to manufacture, has a minimum number of parts, is compact, pleasing in appearance, easy to operate and efficient in use.

For other objects and for a better understanding of the invention, reference may be had to the following detailed description taken in connection with the accompanying drawing, in which:

Fig. 1 is a front perspective view of a cigarette dispenser embodying the features of the present invention;

Fig. 2 is a vertical sectional view taken along line 2—2 of Fig. 1;

Fig. 3 is a fragmentary vertical sectional view taken along line 3—3 of Fig. 1, and

Fig. 4 is an exploded perspective view of the ratchet mechanism, shown partly in section to thereby disclose the interior construction.

Referring more in detail to the drawing, in which similar reference characters designate corresponding parts throughout the several views, there is shown a cigarette dispenser, referred to collectively as 10, including a base 11 having a hollow center 12 in which is disposed a bar of lead 13.

A rectangular housing 14 is secured at its lower end 15 to the base 11 in any suitable manner, with the front and rear walls 16 and 17 respectively rearwardly inclined, substantially as illustrated in Fig. 2. The side walls 18 and 19 of the housing 14 curve rearwardly at each end, the housing being open at its top portion intermediate

2

the upper curved portions of the side walls providing a window 20. A curved closure 21 of transparent plastic or other suitable material fits snugly within window 20 and is pivotally mounted upon pins 22 secured to and extending inwardly from each of the side walls 18 and 19 adjacent the lower edge of window 20, substantially as illustrated in Figs. 1 and 2. The upper edge of the closure 21 is formed with a downwardly extending flange 23 adapted to resiliently engage the upper edge of rear wall 17 whereby to retain the closure in position and to normally close the top of the housing. However, upon upward displacement of the flange 23, the closure 21 may be rotated outwardly to the position shown in dotted lines in Fig. 2, whereby to provide access to the interior of the housing for a purpose to be hereinafter referred to.

A downwardly inclined partition 24 is secured in suitable manner to the rear wall 17 intermediate its ends and serves to divide the housing 14 into upper and lower compartments 25 and 26 respectively, the partition 24 terminating short of the front wall 16 whereby to provide a passage way 27.

The side walls 18 and 19 directly below the partition 24 are formed with laterally aligned bearings 28 and 29 respectively rotatably mounting the ends 30 and 31 of the conveyor roller 32, the end 31 extending outwardly beyond the wall 19 a substantial distance for a purpose to be herein-after referred to.

The roller 32 around its periphery is provided with three equidistant semi-cylindrical grooves 33 extending substantially the length thereof and each adapted to receive a cigarette 34 therewithin, substantially as illustrated in Fig. 3.

Referring now particularly to Fig. 4, it will be seen that the wall 19 on the outer side thereof surrounding the bearing 29 is formed with a circular plug 35 having three equidistant openings 36 intermediate the end 31 and the periphery thereof.

A knob 37 of substantially the same outside diameter as the plug 35 is secured to the outer end of the roller end 31 adjacent the plug 35 and is provided with an annular opening 38 housing a spring 39 surrounding the end 31 and secured at one end to the knob 37.

The other end of the spring 39 is bent into an ear 40 and extends into the openings 36 to engage the sides of the latter and to thereby normally prevent angular rotation of the roller 32. It will be noted, however, that when the knob 37 is rotated manually in a clockwise direction a

sufficient amount, the ear 40 will snap out of one of the openings 36 into the next one thereby indicating to the user by sound and feel of the knob 37 that the knob 37 has been rotated a sufficient amount in a manner to be hereinafter referred to.

A ski-shaped chute 41 having a central opening 42 is secured in suitable manner to the rear wall 17 intermediate its bottom and the partition 24, the chute 41 extending parallel to the partition 24 and outwardly of the housing 14 through an opening 43 in the front wall 16 intermediate the curved lower ends of side walls 18 and 19, substantially as illustrated in Figs. 1 and 2.

In operation, the closure 21 is swung into an open position and the pack of cigarettes emptied into the compartment 25, the roller 32 preventing displacement of cigarettes 34 through the passage way 27. It will be noted that the roller 32 extends above the surface of partition 24 and is freely spaced from the front edge of the latter whereby to permit clockwise rotation of the roller past said edge.

Due to the engagement of ear 40 at all times with one of the openings 36, one of the grooves 33 will always lie above the partition 24 and contain a cigarette 34 forced therein by the weight of the other cigarettes.

Upon manual rotation of the knob 37 in a clockwise direction, the groove 33 containing the cigarette will rotate downward past the partition 24, with the ear 40 snapping into the next clockwise opening 36, thus indicating to the user that the roller has been rotated a sufficient amount to deliver one cigarette. At this point the cigarette will drop freely out of groove 33 onto chute 41, following the course indicated by the dotted arrow in Fig. 2, where it will be retained by the curved ends of the chute above the base 11.

With the closure normally in the closed position, it is apparent that the dispenser will serve as a convenient humidor for the cigarettes, as well as a dispenser. The dispenser will not topple over due to the weight of the lead slab 13, and may also be used as a paper-weight.

While various changes may be made in the detailed construction, it shall be understood that such changes shall lie within the spirit and scope of the invention as defined by the appended claim.

Having thus set forth and disclosed the nature of my invention, what is claimed is:

A cigarette dispenser comprising an upstanding housing of elongated length, a base secured to the bottom of said housing, a removable cover for the top of said housing, a downwardly inclined partition secured to the rear wall of said housing and extending forwardly and downwardly, said partition terminating short of the

front wall of the housing whereby to provide a passageway between a first compartment above said partition and a second compartment below said partition, a roller pivotally mounted in the side walls of said housing below said passageway with the upper surface of said roller extending upwardly into said passageway whereby to close the same, said roller having a plurality of longitudinal recesses each adapted to receive a cigarette, a plurality of cigarettes disposed in said upper compartment and resting freely upon said inclined partition, manually operable means for rotating said roller a fixed amount to deliver one of said cigarettes, said housing having a second opening intermediate the front wall thereof and said base, and a chute extending downwardly and forwardly from the rear wall of said housing below said roller, said chute extending outwardly of said second opening, said means for rotating the said roller a fixed amount comprising an elongated shaft secured to the said roller and extending outwardly therefrom through the said housing at one side thereof, the said shaft being disposed along the longitudinal axis of the said roller, whereby rotation of the said shaft will rotate the said roller, the side wall of the said housing surrounding the said shaft having a plurality of radial grooves equal in number to that of the said recesses in the said roller, a knob secured to the end of the said shaft adjacent the said grooves and having an annular opening surrounding the said shaft and in alignment with and oppositely disposed to said grooves, and a spring surrounding the said shaft within said annular opening, one end of the said spring being secured to the said knob and the other end of the said spring being bent into a loop adapted to resiliently engage one of the said grooves, in order to retain the said roller in any one of a plurality of cigarette receiving positions of the said roller.
